FLETCHING JIG

Walter C. Rohde, Milwaukee, Wis.

Application June 22, 1940, Serial No. 341,979

2 Claims. (Cl. 144—289)

My invention relates to improvements in fletching jigs.

The object of my invention is to provide a fletching jig adapted to high speed production of accurately fletched arrows.

More particularly stated, it is the object of my invention to provide a fletching jig in which the arrow shaft, upon insertion in the jig, will automatically be accurately positioned with reference to a feather-holding clamp so that no inaccuracies of manual placement enter into the fletching operation.

Another object of my invention is to provide in a fletching jig having characteristics of micrometer accuracy with provision for adjustment to vary the pitch of the feather.

In the drawing:

Figure 1 is a side elevation of my fletching jig with a portion of a partially fletched arrow shaft positioned therein, portions of the jig being broken away in vertical section.

Figure 2 is a view of my jig in plan as viewed on a line normal to the axis of an arrow shaft placed in the jig.

Figure 3 is a section on line 3—3 of Fig. 1.

Figure 4 shows the shorter leg of my jig with my floating shaft nock receiver, the dotted lines indicating the movement of the floating parts.

Figure 5 is a section on line 5—5 of Fig. 1 showing portions of the feathers glued to the shaft in their proper positions.

Figure 6 is a detail of one end of a feather clamp fitted with my adjusting means for changing the pitch of a feather.

Figure 7 is a section on line 7—7 of Fig. 6.

Like parts are identified by the same reference characters throughout the several views.

My fletching jig 10 is in general constructed upon a frame having a long leg 11 and a short leg 12 extending upwardly from a base 13 to receive, in notched portions of the legs, an arrow shaft 14 disposed upwardly at an angle to the base 13. This is in accord with accepted practice so that many jigs may be disposed about a turntable closely adjacent to one another for mass production by one operator, the arrow shafts being at such an angle as to permit close positioning of the various jigs.

Each of the legs 11 and 12 is notched as shown at 15 and 16 respectively so that the shaft of the arrow disposed at the bottom of the V'd notch assumes a position which is accurately predetermined with reference to the other structural members of the jig and the accessories used therewith. However, I have found it necessary,

in order that the jig may be rapidly used without sacrificing accuracy, that my new floating indexing shaft nock holder be provided as follows:

Upon the shorter leg 12 of my jig I secure a C-shaped box 17, the lips 18 and 19 of which engage the short leg 12 along its side margins. A screw at 20 fixes this box 17 positively with reference to the leg 12. My floating nock receiver includes a slide block 25 accurately sized to slide in the box 17, the block being centrally apertured to receive a rotatable nock holder 26 comprising a tubular member flanged at 27 and provided with a spring clip 28 upon which the nock 29 of the shaft 14 is readily receivable. Flange 27 freely rotatable with nock receiver 26 with which it unitarily turns is notched or grooved at three points in its periphery and a ball detent 30, spring pressed by spring 31 and screw 32, tends to drop into the grooves whereby to position the shaft 14 alternatively rotatably at points 120° from one another in the rotation of the shaft.

When a shaft 14 is placed in position with its nock 29 upon the spring clip 28 as shown in Fig. 1, the block 25 as released by the operator will drop as far as the V'd notch 16 will permit. Thus, automatically the shaft is accurately positioned with reference to the V'd notch 15 in the long leg of the jig and the first fletching operation may be performed.

It will be noted that the walls of the notched portions of the legs 11 and 12 are straight and parallel. Between them, end guides 35 and 36 of feather clamp 37 are receivable. These guides are rigidly secured to the main clamp fin 38 against which the secondary fin 39 is urged by spring clamp members 40 and 41, the general shape and construction of which will be recognized immediately as comparable to ordinary stationer's clamps. The feather 45 clipped in a manner well known in this art is receivable between the main clamping fin 38 and the secondary clamping fin 39, and the guides 35 and 36 are so placed with reference to the main clamping fin 38 that the glue-coated feather will be placed against the shaft of the arrow as indicated in Fig. 5, upon the true vertical radius of the shaft as shown at 46 in Fig. 5. When the first feather has been placed against the shaft and the glue has dried sufficiently to hold it in position, the clamp 37 may be removed from the feather and the nock holder 26 may be rotated 120° to the point where ball detent 30 will fall into the next groove in the flange 27. Another feather may then be placed in the clamp 37 and applied to the shaft. When this has been re-

peated for the application of the third feather, the fletching operation is complete.

It will be noted that the nock holder 26 has an interior diameter amply sufficient to receive the largest arrow, which, according to common practice, will not exceed three-eighths of an inch in diameter of shaft. It would be obvious from an examination of the drawing that the smallest of arrows, for instance one-quarter of an inch in diameter, will likewise be receivable accurately without any adjustment in the nock holder, since the smaller arrow merely drops deeper in the V of the notch.

It is, of course, well known that experts in archery have their individual preferences as to the use of feathers from the left wing or from the right wing of the bird from which the feathers were taken. The clamp of my fletching jig is made accurately to accommodate this preference, since the main clamp fin 38 is secured to guides 35 and 36 which are milled eight thousandths off center to accommodate the average thickness of the feather. Thus, the arrow fletched for a right hand feather will be placed under a clamp, the secondary clamping fin 39 of which is on the right side as one sights down the arrow from the nock end, and a left hand feather will be placed in the clamp which has been reversed end for end so the secondary fin 39 is on the left.

Many archers prefer that the feathers of their arrows have provision for greater or lesser spin or rotation of the shaft in flight and I provide for adjustment of my clamp 37 to make as accurate placement of the feather as possible. As indicated above, end guides 35 and 36 for the main clamp fin 38 are receivable in the notched portions of the legs 11 and 12 so as to properly and accurately position the feather upon the arrow shaft. In the adjustable construction shown in Figs. 6 and 7 in my drawing, an adjustable guide 50 has an inverted L shape and the short leg 51 of the guide overlies the main clamp fin. This leg 51 of the guide is slotted at 52 to receive a threaded post 53 extending upward from the clamp fin. A threaded knob 54 fitted upon the threaded post thus clamps the adjustable guide 50 in any reasonable range of adjustment upon the fin.

By the means thus described, the position of the arrow upon the shaft may be offset at an angle best suited to the particular archer's technique and may provide for right or left hand rotation of the arrow as it is projected from the bow.

From the above description, it will be seen that a fletching operation may be speeded up and accuracy may be attained, since the simple placement of the nock 29 of the arrow into my fletching nock receiver will cause the arrow to assume an accurately predetermined position as the shaft settles into the V of the notch in each leg of my jig. As each feather is placed in position, rotation of my floating nock receiver to the next index position is easily accomplished without danger that the shaft will be misaligned, and if a particular angle of the feather deviating from the true accurate alignment thereof on the shaft is desired, my adjustable guides 50 provide for such adjustment without sacrificing accuracy.

I claim:

1. A fletching jig having notched legs spaced apart, a feather holding clamp provided with guides at either end thereof for reception in said notches, an arrow shaft receiving nock holder adjacent one of the legs whereby to position an arrow therein beneath the feather holding clamp, the guides for the clamp being positioned with reference to the feather holding clamp to apply the feather in opposite right or left relation to the axis of the arrow shaft and the dimensions of the notches in the legs and of the guides being identical at either end of the jig and clamp whereby the clamp may be reversed.

2. A fletching jig having spaced legs, each leg being notched for the reception of an arrow shaft, the side walls of the notches being parallel, a feather clamp having a main clamp fin and a secondary fin urged thereto by spring pressure, the main fin being provided at either end thereof with a guide, the guides being receivable within the parallel walls of the notches in said legs, whereby to accurately position a feather held by said clamp against the shaft of an arrow in said jig.
